UNITED STATES PATENT OFFICE.

JOHN RAYCROFT, OF BRIDGEPORT, CONNECTICUT, ASSIGNOR OF ONE-HALF TO SARAH RAYCROFT, OF BRIDGEPORT, CONNECTICUT.

SAFETY-RAZOR-BLADE HOLDER.

1,293,546.

Specification of Letters Patent.

Patented Feb. 4, 1919.

Application filed September 20, 1918. Serial No. 254,897.

To all whom it may concern:

Be it known that I, JOHN RAYCROFT, a citizen of the United States, and resident of Bridgeport, in the county of Fairfield and State of Connecticut, have invented certain new and useful Improvements in Safety-Razor-Blade Holders, of which the following is a specification.

My invention relates to new and useful improvements in holders for supporting safety razor blades while stropping the same.

The purpose of the invention is to provide a simple and inexpensive form of holder which may be produced, from sheet metal, by the employment of automatic machinery, and further to construct it so as to readily accommodate any form or size of blade, and finally so that the two parts of the holder may be folded one within the other to occupy a small space when not in use.

With this and further objects in view as will hereinafter be set forth and become apparent, the invention comprises certain features of construction, arrangement and combination of parts as will be more fully specified, designated and claimed in the detailed specification to follow and as will be fully understood from the accompanying drawings forming a part of this specification and upon which—

Figure 1 shows a side elevation of my improved form of safety razor blade holder complete, having a razor blade mounted therein.

Fig. 2 is a side edge view of the blade holder shown in Fig. 1, the blade being omitted.

Fig. 3 is a side elevation of the blade holder as seen from the right of Fig. 2.

Fig. 4 is a cross sectional view, taken on line 4—4 of Fig. 2, through the blade and blade holding member.

Fig. 5 shows an enlarged edge view of the holder in a partially folded position, the blade supporting member being broken away and sprung open for the reception of a blade, and

Fig. 6 shows an enlarged view of the hinged portions of the holder as seen from the opposite side edge of that shown in Fig. 2.

As will be noted from the accompanying drawings, the holder is formed of two pieces of sheet metal and one rivet that pivotally connects the end portions of the two parts

together so that the blade holder proper may be swung around and closed into the handle portion of the holder in substantially the same manner that the blade is closed in to the handle of the old fashioned razor. 60 This holder is therefore naturally used, in stropping a blade, in very much the same manner as the old fashioned razor blade is stropped. It will also be apparent from the construction of my holder that a safety 65 razor blade may be inserted in the holder and the device used as for shaving in the same way that the old style razors are employed.

Referring in detail to the characters of 70 reference marked upon the drawings, 8 represents the handle portion of the holder, and which as will be noted is formed of a single piece of sheet metal that is bent at 9 to form the two sides 10. The adjacent inner 75 faces of these side portions are slightly concave to better form the longitudinal pocket 11. The free end portions of this handle are deflected outward and bent in to form the bearing edges 12 and 13 that engage and 80 bear against the sides of the blade holder. A detent lug 14 is formed on the end portion of one side of the handle while the end of the other side is provided with a cam 15 to engage the blade holding member and 85 support the same as shown in Fig. 6.

A rivet 16 passes through this end portion of the handle and likewise through the pivotal end portion of the blade holder 17 as is clearly shown to hold the parts together. 90

18 represents a safety razor blade which may be of any of the commercial patterns, as shown, or one of the several types provided with holes. The blade holder 17 is made of a strip of sheet metal and is bent 95 back upon itself to form opposite parallel sides 19 between which the blade is clamped. These side portions are also concaved in cross sections, see Fig. 4, so as to form two parallel engaging edges along the inner face 100 of each, that register with the similar engaging edges upon the opposite inner faces of the opposite bar thus producing a firm engagement of the blade when clamped therebetween. The free end 20 of the blade holder 105 member when released normally stands out slightly as shown in Fig. 5 and is indicated by dotted lines in Fig. 2, so that the blade may readily be freed and again positioned therein. A small hole 21 is formed on the 110

- outer face of this end portion so that when the same is pressed down and the parts turned the forward end portion 20 of this handle will be engaged by the edge 13, and 5 the lug 14 will engage the recess and yieldably retain the blade holder in alinement with the handle as indicated in Fig. 2. This free end portion 13 of the handle obviously engages the yieldable member 20 when the 10 handle is adjusted to aline with the blade holder and in any position other than at a right angle of one to the other. The part 14 is formed integral with the forward end portion of the handle and extends in slightly beyond the end 13 of the holder, as shown in 15 Fig. 6, to form a stop for the back edge of the long side 19, to prevent the blade holder from becoming displaced during the operation of stropping a blade.
- 20 From the foregoing description of the construction it will be apparent that in order to place a blade in position the handle and blade holder must first be adjusted at right angles to each other. This will free 25 the end 20 of the blade holder and allow it to spring open for the insertion of a blade. A blade is then placed between the two sides 30 19-19 and the free end 20 of the holder is pressed down against the pivotal end and the handle turned so that the forward edge portion 13 will engage and ride up on the free end of the holder and retain it in its 35 closed position. When the parts have been adjusted so as to aline one with the other as indicated in Figs. 2 and 3, the lug will drop into and engage the pivotal end of the holder to stiffen and support the parts in that position and with relation to each other.
- Having thus described my invention, what 40 I claim and desire to secure by Letters Patent, is—
1. In a safety razor blade holder, the combination of a handle made of one piece of
- sheet metal and folded together to form an elongated pocket and free end portions, a 45 blade holding member also formed of one piece bent together to form two parallel clamping members, one end portion of the holding member being pivotally connected between the open ends of the handle and the 50 other end of the holding member adapted to be engaged under one end of the handle to clamp a blade in the holder.
2. In a safety razor blade holder, the combination of a handle portion formed of one 55 piece of sheet metal and folded together to form a pocket, a blade holder including two parallel clamping members adapted to hold a blade therebetween, one end portion of the holding member being pivotally connected 60 to the handle and the shorter member adapted to be engaged under the end of the handle to clamp a blade in the holder.
3. A safety razor blade holder formed of 65 two pieces of metal pivotally connected together to form a handle and a blade holding member, each part being bent together midway of its length forming parallel side portions and free end portions, one end of the holding member being longer than the other 70 and pivotally mounted between the ends of the handle member, the shorter end of the holding member being adapted to be engaged under the free end of the handle member to clamp the blade, a shoulder upon the handle 75 member to engage the blade holding member in a way to support the same and prevent it from turning upon its pivot.
- Signed at Bridgeport in the county of Fairfield and State of Connecticut this 14th 80 day of September, A. D., 1918.

JOHN RAYCROFT.
